UNITED STATES PATENT OFFICE

FRANCIS M. GODDARD, OF DENVER, COLORADO, ASSIGNOR TO JOHN J. SUTTON, OF DENVER, COLORADO

MULTIGRAPHING ATTACHMENT FOR PRINTING PRESSES

Application filed June 17, 1930. Serial No. 461,719.

My invention relates to printing presses. An important object of the invention is to provide means to imitate typewriting on an ordinary platen printing press.

Another object of the invention is to provide means on such a press whereby the heading may be printed as usual, and at the same time the body of the letter printed to imitate a typewritten letter.

A further object is to provide a ribbon attachment, for printing imitation typewritten letters, that will utilize the ribbon over its entire width and avoid using it in sections only.

A still further object of the invention is to provide simple and effective means for advancing and reversing a ribbon comprised in the invention, while the ribbon is away from the type. Other objects reside in providing practical means for carrying out the foregoing objects.

Novel details of construction and novel combinations and arrangements of parts will appear in the course of the following description. It is also to be understood that this specification only covers an embodiment of the present invention and that changes may be made without departing from the scope and spirit of the invention.

In the drawings, like reference characters designate similar parts in the several views.

Figure 1 is a plan view of an embodiment of the present invention.

Figure 2 is an enlarged elevation looking in the direction of the arrow "A" in Figure 1.

Figure 3 is an enlarged section taken on the line 3—3 of Figure 1.

Figure 4 is a section similar to Figure 3, but showing the parts in different operative positions.

Figure 5 is a section taken on the line 5—5 of Figure 2.

Referring more specifically to the drawings, the reference numeral 6 generally designates a frame applied to a printing press, the platen of which is indicated in dotted lines at 7 in Figure 2. The position of type faces is indicated at 67 with relation to the platen and ribbon.

One side 8 of the frame is parallel with

an end of the platen. As shown, the outer edges of the other three sides of the frame are out of parallel with the adjacent edges and ends of the platen 7. Spools 9 and 10 for a ribbon 12 are mounted on shafts 13 and 14 supported in bearing brackets 15 and 16 on the outer edges of side members 17 and 18 of the frame. Said edges are parallel with each other, and as stated are out of parallel with the edges of the platen.

Therefore, the spools 9 and 10 are parallel, but the ribbon travels obliquely across the platen. This arrangement produces even wear across the width of the ribbon. If the ribbon traveled parallel with the lines of type, there would be worn sections and in between such sections the ribbon would be untouched, as is the case with machines now in use. This feature is adaptable to numerous printing machines now known.

The gripper arms used on platen presses are moved inward toward each other and bolts 19 fasten the frame 6 to the same cross bar (not shown) to which the gripper arms are bolted. Strengthening ribs 20, shown in Figure 1, are approximately in the positions usually occupied by the gripper arms before they are moved inward.

The operating mechanism for the shafts 13 and 14 of the ribbon spools includes a counter shaft 21 extending the width of the frame and carrying right and left-hand worm gears 22 and 23 near its ends. Spur gears 24 and 25 loosely mounted on the spool shafts 13 and 14 respectively are between head 26, keyed on said shafts, and friction rings 27. The rings 27 have integral bushings 68 upon which the gears 24 and 25 rotate and upon which the heads 26 are mounted.

A headed bushing 28 is provided for the portions of the shafts 13 and 14 that project through side member 29 of the frame. Springs 30 and 31 coiled around the shafts 13 and 14 respectively abut against a collar 32 on the shaft and a washer 33 that is at the end of the bushing 28 and engaging one of the flanges 34 of the bearing bracket 16.

The worm gear 22 is disposed between bear-

ings 35 and 36, and the worm 23 is between bearings 37 and 38.

A loosely mounted, elongated gear 39 is provided between a shoulder member 40 on the counter shaft 21 and a collar 41 keyed on the shaft, and has ratchet teeth 42 at its end. The collar 41 also has ratchet teeth 43 to engage the teeth 42 on the collar. A spring 44 between the shoulder 40 and the gear 39, urges the ratchet teeth of the collar and the gear into engagement. A bearing 45 is provided adjacent to the collar.

A spring-urged toggle is connected with the counter shaft 21 to hold one or the other of the worms in engagement with its respective spur gear. The toggle comprises a pivoted arm 46 actuated by a spring 47. A link 48 pivotally connects the arm with a dog 49 mounted on the shaft between collars 50 that are fastened on the counter shaft 21. Bearings 45 and 51 limit movement of the collars 50.

A lever 52, pivoted on a screw 53, has at one end segmental teeth 54 engaging the gear 39. The other end has a flange 55 disposed under the platen, whereby movement of the frame relative to the platen moves the lever after each impression of the press. A coil spring 58 around a boss 59 on the lever tends to return the lever to its original position each time. The spring is hooked around a finger 60 on the frame and project through an opening in the lever, as shown at 61.

As stated, the spur gears 24 and 25 are loosely mounted on bushings 68 on the shafts 13 and 14. However, each gear carries oppositely disposed pins 62 disposed to abut against a cross pin 63. Each of the cross pins passes through the shaft, through the bushing 68, and through the head 26, keying said parts on the shaft. One end of a coiled spring 65 around the boss 59 is fastened to one of the pins 62 on the spur gear, and the other end is fastened to the cross pin 63. This spring holds the spur gear in the position shown in Figure 4, whereby the initial movement of the gear, after the worm engages it, does not rotate the shaft. In fact, the gear may rotate approximately one-half a revolution before the cross pin 63 engages the pins 62 on the gear again, to impart rotary motion to the shaft.

In the operation of the invention, the ribbon travels back and forth obliquely across the type and is automatically reversed at the ends by the mechanism described.

In applying the present invention to a printing press, the ink rollers of the press may be partly cut away so that they will not ink the type that is inked by the ribbon. However, in some instances, it might be advisable to ink all of the type by the rollers on the press. In this latter way, the inked type engaging the ribbon would re-ink the ribbon.

The ribbon is advanced a slight bit between each impression of the printing press, through the intermediary of the flange 55 under the platen by the movement of the frame 6 away from the platen. The movement of the ribbon takes place not only between impressions but also when the ribbon is away from the type. During the advancing movement of the ribbon, it is not dragged across the type, as is usual with ribbon printing apparatus, because the frame 6 moves away from the type faces between impressions, as shown in Figure 6.

The lever teeth 54 rotate the gear 39 a part of a revolution after each impression. When the lever is released, the spring 58 returns the lever to its original position. Rotation of the gear 39 is communicated to the collar 41 and thereby to the counter shaft 21 by means of the ratchet teeth 42 and 43. The spring 44 maintains these teeth in engagement. The counter shaft 21 operates the worms, whose movement is imparted to the spools through the gears 24 and 25 and through shafts 13 and 14. The springs 30 and 31 hold the friction rings 27 in contact with the heads of the bushings 28 to resist rotation of the spools. This resistance holds the ribbon taut.

The spring-urged toggle holds one or the other of the worms in engagement with its respective spur gear, and moving one worm out of engagement and the other into engagement is opposed by the spring 47 on the toggle arm. This opposition holds the mechanism in an operative position during movement of the ribbon.

The ribbon is fastened to the goods by any suitable or conventional means, so that when the ribbon reaches the end, further rotation in the same direction is prevented. Continued rotation of the worms by continued operation of the press, will rotate the worm out of engagement with its spur gear, whereby to cause engagement of the other worm with its spur gear, to reverse the movement of the ribbon.

To prevent the toggle from stopping at dead center, there is a period during the reversing operation that both worms are in engagement with their gears. But the worms do not pull the ribbon in opposite directions, due to the free movement of the spur gears during a portion of their rotation. Both worms are not in engagement long enough to rotate the shafts 13 and 14 in opposite directions.

After the shaft is moved beyond dead center of the toggle, the spring 47 snaps one worm out of engagement and moves the other into a position, whereby the pins 62 and 63 are in engagement. Thus the reversal of the direction of movement of the ribbon is automatic.

The present invention has been found to operate very satisfactorily in actual practice,

nd the printed product is a striking likeness of typewriting, while other parts of work are printed as usual, all in a single operation.

What I claim and desire to secure by Letters Patent is:

1. An attachment for printing presses, comprising a frame, ribbon spools on the frame, driving shafts for the spools, gears on the shafts, driving gear means arranged to engage either of the first mentioned gears, the driving gears being disposed in one position to simultaneously engage both of the first-mentioned gears and adapted by continued movement to move out of engagement with the one and into engagement with the other of the first-mentioned gears, at least one of the gears having a free movement on its shaft during the simultaneous engagement, a spring to return the free moving gear to a predetermined position when disengaged from its respective driving gear, and spring means tending to hold the driving gears in engagement with the respective shaft gears.

2. An attachment for printing presses, comprising a frame, ribbon spools on the frame, driving shafts for the spools, gears loose on the shafts, abutments on the shafts and gears limiting relative movements of the gears and shafts, driving gears adapted to engage either or both of the first-mentioned gears, the abutments being arranged whereby the one or both of the gears rotate freely on the shaft during the simultaneous engagement, the driving gears being adapted to move out of engagement with one or the other of the first noted gears by continued rotation.

3. An attachment for printing presses, comprising a frame, ribbon spools on the frame, driving shafts for the spools, gears having limited movements on the shafts, driving gears for the first-mentioned gears, and springs to return the first-mentioned gears to predetermined positions after being disengaged from their respective driving gears.

4. An attachment for printing presses, comprising a frame, ribbon spools on the frame, driving shafts for the spools, gears on the shafts, driving gear means arranged to engage either of the first-mentioned gears, the driving gears being disposed in one position to simultaneously engage both of the first-mentioned gears and adapted by continued movement to move out of engagement with the one and into engagement with the other of the first-mentioned gears, at least one of the gears having a free movement on its shaft during the simultaneous engagement, and spring means tending to hold the driving gears in engagement with the respective shaft gears.

5. A printing press comprising rotary shafts, spools on the shafts, a ribbon on the spools, and reversible means to rotate the

shafts, and thereby move the ribbon, in opposite directions, said means including gears at least one of which has a limited free movement on its shaft and driving gears to rotate the first-mentioned gears, the driving gears being in engagement with both of the first-mentioned gears during a period in the reversing operation and said free movement preventing the spools from pulling the ribbon simultaneously in the opposite directions.

In testimony whereof I hereunto affix my signature.

FRANCIS M. GODDARD.
